UNITED STATES PATENT OFFICE.

RUSSEL G. WOODWARD, OF WAUKEGAN, ILLINOIS, ASSIGNOR TO UNION

SPECIFICATION forming part of Design No. 34,730, dated July 2, 1901.

Application filed June 6, 1901. Serial No. 63,466. Term of patent 14 years.

To all whom it may concern:

Be it known that I, RUSSEL G. WOODWARD, a citizen of the United States, residing at Waukegan, in the county of Lake, State of Illinois, have invented a certain new and original Design for a Sewing-Machine Frame, of which the following is a description, reference being had to the accompanying drawing and to the letters of reference marked thereon.

10 My invention relates to a new and original design for sewing-machine frames and for bed-castings; and it consists in a design for sewing-machine frames of the shape and configuration hereinafter shown and described.

15 In the accompanying drawing the figure is a perspective view of a sewing-machine frame or casting embodying my design:

In the drawing, A represents the bed, which is provided with the depression a.

20 B is the standard, rising from the rear portion of the bed and having the gooseneck or overhanging frame C. This gooseneck or overhanging frame C is provided at its forward end with the angular projecting lugs b c, provided with openings which register with 25 each other and with the lug d, which has a transverse opening e through it. The forward end of said overhanging frame or gooseneck C is also provided with the inclined opening f and the cut-away portion g.

30 The leading feature of the design consists in the shape and configuration of the frame.

Having thus described my invention, what I claim, and desire to secure by Letters Patent, is—35 The design for a sewing-machine frame; substantially as shown and described.

In testimony whereof I affix my signature in presence of two witnesses.

RUSSEL G. WOODWARD.
